UNITED STATES PATENT OFFICE.

GRANVILLE T. SHEPLEY, OF TOWNSEND, MASSACHUSETTS.

NAIL.

SPECIFICATION forming part of Letters Patent No. 451,213, dated April 28, 1891.

Application filed November 6, 1890. Serial No. 370,526. (No model.)

To all whom it may concern:

Be it known that I, GRANVILLE T. SHEPLEY, of Townsend, county of Middlesex, State of Massachusetts, have invented certain new and useful Improvements in Nails, of which the following is a specification, reference being had to the drawings accompanying and forming a part hereof, in which—

Figures 1 and 2 are representations of wire 10 nails embodying my improvement, and Fig. 3 is a perspective of a cut nail also embodying my improvement.

It frequently happens that carpenters and others who are nailing a piece of wood in place 15 desire to secure it temporarily, but firmly, until they see that it is in the right position or until some adjoining piece is properly secured, and then afterward drive the nails home and secure the piece permanently. In such cases it often happens that the nails securing the wood must be withdrawn and the 20 position of the piece changed. If the temporarily-secured piece of wood is firmly secured, the nails require to be driven in to the head, and in such case if they afterward are withdrawn the wood is marred and the finish 25 damaged.

My invention has for its object to produce a nail which may be used to secure a piece 30 temporarily and at the same time will secure it firmly, and which may be withdrawn to change the position of the piece readily, and without danger of marring the finish; and it consists in a double-headed nail, the lower 35 head being of equal or less size than the upper head and in close proximity thereto, as shown and described, and as is more particularly pointed out in the claim which is appended hereto and made a part hereof.

40 In the accompanying drawings I have shown several forms of nail embodying my invention; but it will be clear that the precise shape of

the nail or of the heads is not essential to my invention.

My improvement is simple and will be readily understood from the accompanying drawings and the following description.

a is the shank of the nail.

b is the upper head, and *c* is the lower head. The lower head should not be of larger diameter than the upper head, because when the nail is finally driven home the upper head should be sufficient in size to fill the hole made by the under head, in order that the work may be neatly and properly finished. 55 The upper and under heads may be connected by a short neck of less diameter than either of the heads, so that the under head will be in close proximity to the upper head; or the neck may be of a diameter equal to or substantially equal to that of the under head, the object being to separate the heads sufficiently to permit of the upper head being grasped by the claw of a hammer or other device for withdrawing the nail. The shoulder at *d* underneath the lower head is preferably sloping; but in the case of cut nails where the nail is flat and narrow it may be square, as shown at *d'*.

I am aware that nails have been made with a flange underneath the head where the head 70 was not intended to be driven into the material, and also that nails have been made with detachable heads, such as are employed for picture-nails, and I do not claim such; but

What I do claim is—

A nail having two heads which are in close proximity to each other, the under head having a diameter which is equal to or less than that of the upper head, substantially as and for the purpose set forth.

GRANVILLE T. SHEPLEY.
